CLEANING EQUIPMENT AND THE LIKE**

Glen L. Groth, 26 Andrew Drive,
Tiburon, Calif.

Filed Dec. 14, 1967, Ser. No. 9,772

Term of patent 14 years

U.S. Cl. D80—10
Int. Cl. D6—01

FIG. 1

FIGURE 1 is a front perspective view of a lockable display rack for floor cleaning equipment and the like showing my new design;

FIGURE 2 is a side elevational view thereof; and

FIGURE 3 is an enlarged view of a portion of my rack's device-retaining means, and is in the same perspective as FIGURE 1. The broken line representation of a lock in FIGURE 2 is for the purpose of illustration only.

I claim:

The ornamental design for a lockable display rack for floor cleaning equipment and the like, substantially as shown and described.
